UNITED STATES PATENT OFFICE.

IRA KARNS, OF PRAIRIE DEPOT, OHIO.

STUFFING-BOX.

SPECIFICATION forming part of Letters Patent No. 678,714, dated May 7, 1901.

Application filed January 17, 1901. Serial No. 43,664. (No model.)

To all whom it may concern:

Be it known that I, IRA KARNS, a citizen of the United States, residing at Prairie Depot, in the county of Wood and State of Ohio, have 5 invented new and useful Improvements in Stuffing-Boxes, of which the following is a specification.

My invention relates to improvements in that class of stuffing-boxes which comprise a 10 weighted lever for exerting pressure on the packing surrounding a reciprocatory rod and which are designed more particularly for use on oil-well tubes with a view of preventing the loss of oil incident to the pumping operation.

It consists in a certain peculiar and practical construction the novelty, utility, and advantages of which will be fully understood from the following description and claims 20 when taken in conjunction with the accompanying drawings, in which—

Figure 1 is a side elevation illustrating my improved stuffing-box in its proper operative position. Fig. 2 is a top plan view of the same, 25 and Fig. 3 is a detail section illustrating the stuffing-box case and the packing and gland or follower therein.

In the said drawings similar letters of reference designate corresponding parts in all of 30 the views, referring to which—

A is an oil-well pipe or tube threaded at its upper end.

B is the case of my improved stuffing-box, which is threaded at its lower end to take into 35 the upper end of the pipe or tube A and is provided with an exterior flange *a* to rest on the upper end of the pipe or tube and form a wrench-hold, and also with a bore *b*, gradually contracted at *c* to a diameter slightly greater 40 than that of the pump-rod C.

D is packing arranged in the lower part of the bore of casing B.

E is the gland or follower, arranged in the bore of casing B above the packing D and 45 provided at its upper end with diametrically opposite lugs *d*, rounded on their upper sides and equipped with guard-flanges *e*, and F is a bracket which surrounds the case B and is clamped thereon by means of a screw *f*. The 50 said bracket, which is readily attachable to stuffing-box cases such as at present in use, is provided with oppositely-extending long

and short arms *g* *h*, both of which terminate at their outer ends in vertically-disposed eyes, as shown.

G is a forked lever which straddles the pump-rod and is provided in the lower edges of the arms of the fork with rounded notches *i* to receive the lugs *d* on the gland or follower E. The said lever is provided adjacent 60 to one of its ends with teeth or serrations *j* for the engagement of the hanger *k* of an adjustable weight H, and at its opposite end it has a transverse bolt *l*, which bridges its fork and is designed for the pivotal connection of 65 a depending rod I, the latter being held in its position midway between the arms of the fork by spacing-collars *m*, as best shown in Fig. 2. The rod I extends downwardly through the eye of the bracket-arm *h* and is provided below 70 the same with a securing-nut *n*.

It will be readily apparent from the foregoing that the lever G is connected in a hinged manner to the upper end of the rod I and bears loosely on the upper end of the 75 gland or follower E at a point intermediate of the rod I and the weight H. From this it follows that the weight, through the medium of the lever G, will exert constant downward pressure on the packing in the case B and will 80 crowd said packing down into the contracted portion of the bore of the case, with the result that the packing is constantly pressed inwardly against the pump-rod and a tight joint effected which precludes leakage of the 85 oil incident to the up-and-down movements of the rod. It also follows that by virtue of the lever being bifurcated and arranged to straddle the pump-rod there is nothing to prevent downward movement of its weighted 90 end within certain limits, and therefore as the packing wears away the weighted lever will move the gland or follower downwardly and the latter will compress the packing into a gradually-decreasing space, but always with 95 the same pressure, around the pump-rod. This operation continues until the packing is worn away and the gland is stopped by its flange at the top, when of course it is necessary to repack the box.

In cold weather when the pump has been idle for a time the packing adheres to the pump-rod and at the first upstroke of said rod the packing, gland, and lever would be

lifted clear of the case B but for the provision of a rod J, which may be properly termed a "stop-rod." This rod is pivotally connected to the weighted arm of the lever G, extends loosely through the eye of bracket-arm g, and is provided below the same with a nut p or other suitable enlargement. Being extended loosely through the arm g of the bracket, the stop-rod will not interfere in any manner with the free downward movement of the lever G, which operates to compress the packing in the case B and around the rod C, as before described. In the event, however, that the gland, packing, and lever tend to move upwardly with the pump-rod on the first upstroke of the latter the enlargement p of the stop-rod by engaging the bracket-arm g will limit the upward movement of the lever, and thereby effectually prevent raising of the gland or follower E clear of case B.

It will be appreciated from the foregoing that by virtue of the construction of my improved stuffing-box it requires no attention or adjustment from the time the packing is placed in the case B until it is entirely worn away; but, on the other hand, the gland E and the weighted lever G are calculated to accommodate themselves to the depletion of the packing, with the result that the packing is held under the same pressure around the reciprocating pump-rod until the gland is stopped by its flange bringing up against the upper end of the case B.

Having described my invention, what I claim, and desire to secure by Letters Patent, is—

1. In a self-adjusting stuffing-box, the combination of a case adapted to receive a recip-

rocator rod, packing arranged in said case, a gland or follower also arranged in the case and on the packing, and having rounded lugs on its upper end at opposite sides of its bore, provided with guards, a bracket clamped on the case and having an arm disposed laterally thereto, a rod rising from said bracket-arm, and a forked lever having rounded notches in the arms of its fork, and also having said arms arranged on the lugs of the gland at the inner sides of the guards; the said lever being connected at one end in a hinged manner to the rod rising from the bracket-arm, and provided adjacent to its opposite end with an adjustable weight.

2. In a self-adjusting stuffing-box, the combination of a case, packing therein, a gland also arranged in the case and on the packing, bracket-arms connected with and extending in opposite directions from the case; one of said bracket-arms having an eye, a rod rising from the other bracket-arm, a lever bearing loosely on the gland and connected at one end in a hinged manner to the rod rising from one bracket-arm, and having a weight at or adjacent to its opposite end, and a rod pivotally connected to the weighted arm of the lever and extending loosely through the eye in the bracket-arm, and provided below said arm with an enlargement adapted to engage the same, substantially as specified.

In testimony whereof I have hereunto set my hand in presence of two subscribing witnesses.

IRA KARNS.
